Primary Examiner — Cynthia M Chin(74) *Attorney, Agent, or Firm* — John H. Choi(57) **CLAIM**

The ornamental design for a tent, as shown and described.

DESCRIPTION

FIG. 1 is a perspective view of a tent showing my new design;

FIG. 2 is a top view thereof;

FIG. 3 is a bottom view thereof;

FIG. 4 is a front view thereof, the rear view thereof being a mirror image of that which is shown; and,

FIG. 5 is a left side view thereof, the right side view thereof being a mirror image of that which is shown.

The features shown in broken lines depict environmental or other associated subject matter and form no part of the claimed design.
